DESIGN FOR AN OLIVE AND PICKLE FORK

George J. Capewell, Jr., Hartford, Conn., assignor
to The Capewell Manufacturing Company,
Hartford, Conn., a body corporate of Connecti-
cut

Application April 18, 1940, Serial No. 91,759

Term of patent 14 years

To all whom it may concern:

Be it known that I, George J. Capewell, Jr., a citizen of the United States and a resident of Hartford, in the county of Hartford and State of Connecticut, have invented a new, original, and ornamental Design for an Olive and Pickle Fork, of which the following is a specification, reference being had to the accompanying drawing, forming part thereof, in which—

Figure 1 is an edge elevational view of an olive and pickle fork showing my new design.

Figure 2 is a rear elevational view of the same.

Figure 3 is a front elevational view thereof partly in perspective.

I claim:

The ornamental design for an olive and pickle fork, as shown.

GEORGE J. CAPEWELL, JR.
